UNITED STATES PATENT OFFICE

167,888

TOY AUTOMOBILE

Robert I. Genin, Hollis, and Gerald E. Stahl, Rye,
N. Y., assignors to Archer Plastics, Inc., Astoria,
N. Y.

Application February 8, 1952, Serial No. 18,447

Term of patent 3½ years

(Cl. D34—15)

To all whom it may concern:

Be it known that we, Robert I. Genin, a citizen of the United States, residing at Hollis, county of Queens, and State of New York, and Gerald E. Stahl, a citizen of the United States, residing at Rye, county of Westchester, and State of New York, have invented a new, original, and ornamental Design for a Toy Automobile, of which the following is a specification, reference being had to the accompanying drawing, constituting a part thereof.

Figure 1 is a side elevational view of a toy automobile, embodying our new design;

Fig. 2 is a top view;

Fig. 3 is a front elevational view.

We claim:

The ornamental design for a toy automobile, substantially as shown.

ROBERT I. GENIN.
GERALD E. STAHL.
